UNITED STATES PATENT OFFICE.

EMILY C. UNDERHILL, OF NEW YORK, N. Y.

DESIGN FOR A MEDICINE-SPOON.

SPECIFICATION forming part of Design No. 16,033, dated April 7, 1885.

Application filed February 24, 1885. Term of patent 11 years.

To all whom it may concern:

Be it known that I, EMILY C. UNDERHILL, of West Farms, in the city, county, and State of New York, have invented and produced a new and original Design for a Medicine-Spoon, 5 of which the following is a specification.

Reference is to be had to the accompanying drawings, forming a part of this specification, in which similar letters of reference indicate 10 corresponding parts in both the figures.

Figure 1 is a plan view of my newly-designed medicine-spoon, and Fig. 2 is a side elevation of the same, these two views being deemed necessary to fully illustrate my design.

15 The leading features of my design are the tapered and elongated bowl having a tapered and elongated rounded cap, and having a slightly flattened and flaring nozzle, and the shoulders or beads on the bowl having the same shape as the contour of the bowl.

20 A is the handle of the spoon. B is the bowl,

which is covered in its forward part with a rounded cap, C. The bowl B and cap C are tapered and elongated in their form, and have upon their ends a slightly flattened and flaring nozzle, D. Upon the bowl B are shoulders or beads E, having the same form as the outline of the bowl.

I claim—

1. The design for a medicine-spoon herein 30 shown and described, the same consisting of the tapered and elongated bowl B, having a tapered and elongated rounded cap, and having a slightly flattened and flaring nozzle.

2. The design for a medicine-spoon herein 35 shown and described, the same consisting of the shoulders or beads on the bowl, and having the same shape as the contour of the bowl.

EMILY C. UNDERHILL.
